United States Patent Office

Des. 195,898
Patented Aug. 6, 1963

195,898

BOTTLE

Bruce L. Roberts, Rossford, Ohio, assignor to Owens-Illinois Glass Company, Toledo, Ohio, a corporation of Ohio

Filed Nov. 14, 1962, Ser. No. 72,494

Term of patent 14 years

(Cl. D58—6)

FIG. 3

FIG. 1

FIG. 2

FIG. 4

FIG. 5

FIG. 6

I claim:
The ornamental design for a bottle, substantially as shown.
